Assistant Examiner — Benjamin D. Wannemacher

(57) **CLAIM**

The ornamental design for a socket plug tool as shown and described.

DESCRIPTION

FIG. 1 is a perspective view of a socket plug tool, showing our new design.

FIG. 2 is a front view of the claimed design.

FIG. 3 is a rear view of the claimed design.

FIG. 4 is a top view of the claimed design.

FIG. 5 is a bottom view of the claimed design; and,

FIG. 6 is a cross-sectional view of the claimed design.

The arrow lines appearing on FIG. 3 indicate a cross-sectional view of FIG. 6.
